CLAIM

The ornamental design for a package with locking mechanism as shown and described.

DESCRIPTION

FIG. 1 is a top perspective view of an outer box of the package with locking mechanism showing our design, showing the outer box;

FIG. 2 is a bottom perspective view of the outer box;

FIG. 3 is a top perspective view thereof, showing the inner tray with the long flap unfolded, and tab features open;

FIG. 4 is top perspective view of the inner tray with the long flap folded, and tab features open;

FIG. 5 is an exploded top and side perspective view, showing the direction in which the inner tray inserts into the outer box;

FIG. 6 is an exploded bottom and side perspective view, showing the direction in which the inner tray inserts into the outer box;

FIG. 7 is a top perspective view thereof, showing the inner tray partially inserted into the outer box;

FIG. 8 is a front view of the outer box;

FIG. 9 is a back view of the outer box;

FIG. 10 is a left side view of the outer box, showing locking mechanism partially open;

FIG. 11 is a right side view of the outer box, showing locking mechanism partially open;

FIG. 12 is top view of the outer box;

FIG. 13 is a bottom view of the outer box;

FIG. 14 is a front view of the inner tray;

FIG. 15 is a back view of the inner tray;

FIG. 16 is a left side view of the inner tray;

FIG. 17 is a right side view of the inner tray;

FIG. 18 is a top perspective view of the inner tray with the insert tabs lifted;

FIG. 19 is a top view of the inner tray;

FIG. 20 is a bottom view of the inner tray;

(Continued)

FIG. 21 is top perspective view plan view, showing the inner tray inserted fully into the outer box;
FIG. 22 is a top view of the inner tray fully inserted into the outer box;
FIG. 23 is a back view of the inner tray fully inserted into the outer box;
FIG. 24 is a left side view of the inner tray, fully inserted into the outer box, showing locking mechanism partially open;
FIG. 25 is a right side view of the inner tray, fully inserted into the outer box, showing locking mechanism partially open;
FIG. 26 is a top view of the inner tray fully inserted into the outer box; and,
FIG. 27 is a bottom view of the inner tray fully inserted into the outer box.
The dash-dot broken lines represent an exploded configuration and form no part of the claimed design.
